UNITED STATES PATENT OFFICE

GILMAN L. PALMER, OF CONNEAUT, OHIO.

METAL SIGN-BOARD.

1,104,921.

Specification of Letters Patent. Patented July 28, 1914.

Application filed October 31, 1911. Serial No. 657,791.

To all whom it may concern:

Be it known that I, GILMAN L. PALMER, a citizen of the United States, residing at Conneaut, in the county of Ashtabula and State of Ohio, have invented certain new and useful Improvements in Metal Sign-Boards, of which the following is a specification.

My invention relates to an improvement 10 in metal sign boards, and the object is to provide a frame to which the panels can be applied or removed at any time. The panels are constructed of an angle iron frame, which is made from a single piece of material, preferably rectangular in shape, and over which frame is stretched a metal body, the edges of the metal body extending over and along the vertical sides of the angle iron frame and then broken around the edge 15 thereof, so that the metal body is securely fastened to the angle iron frame. The angle iron frame is fastened to the skeleton frame, and each panel is connected to the adjacent panel, so that the edges are held 20 snugly together and in alinement.

The invention consists in certain novel features of construction and combinations of parts which will be hereinafter described and pointed out in the claims.

30 In the accompanying drawings, Figure 1 is a perspective view; Fig. 2 is a vertical sectional view; Fig. 3 is a rear view of one of the panels; Fig. 4 is a horizontal section of one of the panels; and Fig. 5 is a detail 35 sectional view, showing the manner of connecting the adjacent panels together.

The main frame consists of angle iron posts 1, 1, to which are connected horizontal angle iron bars 2, 2. The horizontal bars 40 are connected to the posts by means of bolts 3 and nuts 4. Strips or braces 5, 5, are connected to the posts for holding the posts in a vertical position.

The panels consist of angle iron frames 6, 45 which are each formed from a single piece of angle iron, which are mitered at the corners as at 7, to allow the angle iron to be bent to form a square corner, and the ends are fastened together in any suitable manner. The angle iron frames 6 are fastened to the horizontal bars 2 by means of bolts 8 and nuts 9. The metallic body 10 is placed upon the flat or horizontally extending surface of the angle iron frames, and the edges 50 11 of the body are bent around the vertical sides 12 of the angle frame, and the extreme

ends of the body are bent at an angle to the edges 11, as shown at 13, so that the body 10 is securely fastened to the angle frame. After the longitudinal edges have been bent 60 at an angle to the main body forming the portions 11 and 13, the metallic body is slid upon an angle-iron frame 6. Then the angle-iron frame with the panel or metallic body 10 secured thereto is mounted on the 65 horizontal bars 2 where the frame is fastened. In this manner the panel body can be mounted upon the frame and will be held thereto by means of the flanges or portions 11 and 13, and when two panels are placed adjacent to each other the adjacent edges of the frames and panels will be fastened together by means of bolts 14 as is shown clearly in Fig. 5. After the metallic body has been applied to the angle frames 6, the 70 angle frame is connected to the horizontal bars 2 by the bolts and nuts 8 and 9, respectively. Then the adjacent sections or panels are connected together by means of bolts 14, which pass through the vertical 75 sides 12 and edges 11 of the angle iron frame and metallic body, as clearly shown in Fig. 5.

Having fully described my invention, what I claim as new and desire to secure by 85 Letters Patent, is:—

1. A panel composed of an angle iron frame of rectangular form and a sheet metal covering, the two opposite edges of which are bent along two lines approximately parallel with each other with the extreme edges extending inwardly approximately parallel with the main portion of the sheet metal covering, the outer flanges of opposite sides of the angle iron frame fitting the space between the main portion of the sheet metal covering and the inwardly turned flange at the extreme edge, and the other side of the angle iron resting against the main portion of the sheet metal covering in connection 90 with a support composed, partly, at least, of angle irons, within the angles of which the ends of the panel fit.

2. In a sign board, a panel composed of sheet metal, the opposite edges of which are bent along two parallel lines, and a rectangular angle iron frame which the bent edges of the sheet metal embrace, the angle of the angle iron frame located in the angle formed between the main portion of the sheet metal 100 and the adjacent side flanges formed by the bend, and a support for the opposite 110

ends of the panel made of angle iron, one flange projecting outwardly to embrace an end of the panel, and means passing through said outwardly projecting flange and inwardly projecting flange of the end of the panel for securing the end of the panel to the support.

In testimony whereof I affix my signature, in the presence of two witnesses.

GILMAN L. PALMER.
